COIN SEPARATOR AND SLUG EJECTOR

Christian Gabrielsen, Mountain Lakes, N.J., assignor to
Rowe Manufacturing Co., Inc., Whippany, N.J., a cor-
poration of New York

Filed Nov. 16, 1954, Ser. No. 469,183

6 Claims. (Cl. 194—99)

My invention relates to a coin separator and slug ejector for use with coin-operated machines and more particularly to an improved coin separator and slug ejector which is simple in construction, which is certain in operation, and which may readily be disassembled for cleaning.

In machines, the operation of which is responsive to the deposit of coins therein, some means must be provided for separating the various denominations of coins from each other before the coins reach the mechanism to be actuated thereby. It is necessary, also, in such machines that spurious coins, counterfeit coins, or slugs be separated from genuine coins, prevented from reaching the coin-actuated mechanism or coin register and ejected from the machine. Various means and mechanisms have been suggested in the prior art for classifying deposited coins and separating them into the various denominations. Means also are provided in devices of the prior art for arresting the movement of certain types of spurious coins toward the coin register and for separating other types of spurious coins from true coins. Some devices of the prior art employ magnets to arrest the movement of ferrous slugs toward the coin register. When such a magnet is employed, scavenging means must be provided for freeing the coin from the magnet and ejecting it from the machine. One scavenging device employed in the prior art generally is an arm which sweeps across the face of the keeper magnet when the scavenging mechanism is operated. This construction is complicated and involves the use of a member which must enter into the coin track of the machine. In the event this arm becomes stuck or deranged for any reason, the entire coin separator must be disassembled to remedy the difficulty. The machines of the prior art also generate eddy currents by means of magnets for affecting the trajectory of coins or slugs leaving the coin track to direct the coins toward an acceptance or a rejection opening. It will readily be appreciated that the operation of such eddy current generating means is critical and the trajectory of a coin or slug will also depend upon the initial velocity of the coin being tested as it enters the field of the eddy current generating assembly. Most machines of the prior art are not intended to receive pennies. However, pennies are very often intentionally or accidentally deposited in the coin slot of the machine. Because of their size and weight they may become stuck in the coin passage of the machine and prevent further operation of the coin separator. The coin separators of the prior art are generally formed as a unit with many of the operating parts enclosed by fixedly mounted or fixedly hinged plates. It will readily be appreciated that these coin separators, no matter how accurately they perform their function of separating slugs from coins, may become inoperative for many reasons. For example, paper, gum, syrup, or the like deposited in the coin slot by vandals may render the mechanism inoperative. Further, even the ordinary accumulation of dirt in the course of

2

normal use may so affect the mechanism that it does not properly perform its function. In coin separators and slug ejectors of the prior art, a costly and time-consuming disassembly of the mechanism must be undertaken when it becomes necessary to clean the mechanism.

5 I have invented an improved coin separator and slug ejector which is extremely simple in construction, which is certain in operation, and which may readily be disassembled for cleaning. Further, my improved coin separator and slug ejector overcomes many of the difficulties inherent in similar devices of the prior art. I have provided my structure with a swingably mounted ferrous keeper magnet which is operated by the scavenging mechanism to scrape a caught slug off the face thereof. Thus I have obviated the necessity for employing a member which must sweep into the coin path of the device. Further, I have provided brakes for slowing coins as they leave the various coin tracks to enter the field of my eddy current separating means. Thus I accomplish 15 a more accurate separation of spurious coins from true coins in accordance with the material of which they are constituted. Further, my device may readily be disassembled so that access may be had to all operating parts with a minimum of disassembly operations.

20 25 One object of my invention is to provide a coin separator and slug ejector which is simple in construction, which is certain in operation, and which may readily be disassembled and assembled.

25 30 Another object of my invention is to provide a coin separator and slug ejector which overcomes the disadvantages of analogous devices of the prior art.

Other and further objects of my invention will appear from the following description.

35 In general, my invention contemplates the provision of a coin classifier in which coins are separated into their denominations roughly according to size and weight. A pair of scales are provided for weighing quarters and nickels. Coins smaller than a nickel are not weighed, but pass to the dime passageway. After coins have 40 been thus roughly classified by size and weight, they are tested for proper composition by means of an eddy current generating device in the form of permanent magnets. The arrangement is such that coins of a proper composition will have a correct residual momentum to 45 pass between a pair of separating points. Coins having a greater residual momentum than that desired are bounced by one separating point to the coin return chute. Coins having a smaller residual momentum than that 50 possessed by a genuine coin are bounced by another separating point to the coin return chute. The permanent magnets and separating points are mounted upon carrying plates which may be rapidly and conveniently removed for cleaning and adjustment. The mounting plates may 55 employ the magnetism of the eddy current generating magnets to retain the mounting plates in position in my assembly. My invention contemplates the provision of a coin separator and slug ejector for coin-operated machines which includes a coin slot for receiving coins for conditioning for operation the machine with which 60 my device is used. Immediately adjacent the coin slot in the path of travel of all coins deposited in the slot I arrange a catcher for arresting the movement of washers or spurious coins formed with holes. This washer catcher is also arranged to operate as an antitilt device which 65 prevents the passage of all coins including spurious coins, slugs, and true coins into the device when the machine is tilted. Following the washer catcher I provide a common coin passage through which all coins passing by the washer catcher are to travel. Adjacent this coin path 70 I mount a ferrous keeper magnet for arresting the further movement of a slug of ferrous material. Also disposed

in this passage are scales which are weighted to be tilted by coins of various denominations. Each scale tilts to dump or pass a coin of a weight equal to that for which the scale is set in one of a number of coin tracks provided in the machine. Each of the coin tracks of the machine is adapted to receive a coin of a particular denomination. For example, if the assembly is to handle nickles, dimes, and quarters, three coin tracks are provided. Arranged in each of the coin tracks I provide eddy current generating means for aiding in separating true coins from spurious coins according to their composition. A braking device is mounted at the point along each of the coin tracks at which a coin to be tested enters the field of the eddy current generating device. These brakes temporarily arrest the movement of a coin or slug along the path of travel before the coin or slug comes under the influence of the eddy current generating permanent magnet. These eddy current devices assist in directing true coins toward a true coin discharge opening and in directing slugs toward a slug discharge opening. In order to eject slugs which are caught by the washer catcher or by the ferrous keeper magnet, I provide my device with scavenging means. This scavenging means also moves stuck coins, such as pennies, out of the common coin passage and ejects such coins from the machine.

In the accompanying drawings which form part of the instant specification and which are to be read in conjunction therewith and in which like reference numerals are used to indicate like parts in the various views:

Figure 1 is a perspective view of my improved coin separator and slug ejector when viewed generally from one side thereof.

Figure 2 is a perspective view of my improved coin separator and slug ejector when viewed generally from the other side to that shown in Figure 1.

Figure 3 is a perspective view, drawn on a reduced scale, of my improved coin separator and slug ejector with one of the eddy current magnet mounting plates removed to show the quarter coin track of the assembly.

Figure 4 is a perspective view, drawn on a reduced scale, of the eddy current generating magnet mounting plate which was removed from Figure 3.

Figure 5 is a sectional view of my improved coin separator and slug ejector taken generally along the path of travel of a twenty-five-cent coin deposited in the assembly.

Figure 6 is a perspective view, drawn on a reduced scale, of my improved coin separator and slug ejector with one of the eddy current generating magnet mounting plates removed to show the dime and nickel coin tracks of the assembly.

Figure 7 is a perspective view, drawn on a reduced scale, of the eddy current generating magnet mounting plate which was removed from Figure 6.

Figure 8 is a sectional view of my improved coin separator and slug ejector taken generally along the path of travel of a five-cent coin.

Figure 9 is a sectional view, drawn on a reduced scale, of my improved coin separator and slug ejector taken generally along the path of travel of a ten-cent coin.

Figure 10 is a fragmentary elevation, drawn on a reduced scale, of my improved coin separator and slug ejector with parts broken away.

Figure 11 is a fragmentary elevation, drawn on a reduced scale, of my improved coin separator and slug ejector showing the pivotally mounted ferrous keeper magnet and washer catcher.

Figure 12 is a sectional view of my improved coin separator and slug ejector taken along the line 12—12 of Figure 10.

Figure 13 is a fragmentary sectional view of my improved coin separator and slug ejector taken along the line 13—13 of Figure 10.

Figure 14 is a fragmentary sectional view of my im-

proved coin separator and slug ejector taken along the line 14—14 of Figure 10.

Figure 15 is a fragmentary sectional view of my improved coin separator and slug ejector taken along the line 15—15 of Figure 10.

Figure 16 is a fragmentary perspective view, with parts removed, of my improved coin separator and slug ejector showing the means for wiping the portion of the common coin channel adjacent the entrance to the dime coin track.

Figure 17 is a schematic view showing trajectories of various slugs or coins of different material as they leave a coin track after having passed through the field of the eddy current generating means.

More particularly, referring now to Figures 1 and 2 of the drawings, my improved coin separator and slug ejector includes a main mounting plate 10 which may be formed of sheet metal or the like and bent along the edges to form the sides 12 and 14 of the assembly. The upper left-hand corner of the plate 10, as viewed in Figure 1, is shaped to form three sides of a coin slot, indicated generally by the reference character 16. The upper portion of plate 10 also forms the stationary wall of a common coin channel which receives coins deposited in the coin slot 16. In order to complete the coin slot and to complete the common coin channel, I pivotally mount a movable wall 18 adjacent the top of plate 10, as viewed in Figures 1 and 2. Movable wall 18 is formed of any material, such as sheet metal or the like, and is provided with a pair of ears 20 and 22, seen in Figure 2. A pair of ears 24 and 26 formed in the upper edge of plate 10 provide a means by which the movable wall 18 may be mounted on plate 10 by means of its ears 20 and 22. As can best be seen by reference to Figures 2 and 3, a rod 28 passes through all the ears 20, 24, 22, and 26 to provide a pivotal connection between movable wall 18 and the plate 10. Movable wall 18 is provided with an inclined portion 30 which cooperates with the portion of plate 10 which is shaped to form the coin slot.

All coins which are deposited in the coin opening 16 pass into the common coin passage or channel formed by the upper portion of the plate 10 and the movable wall 18. This channel will be described in detail hereinafter. In order to prevent the passage of washers, or other spurious coins formed with holes, from the coin opening 16 into the common coin channel, I arrange a washer catcher, indicated generally by the reference character 32, in the path of coins traveling from the opening 16 into the common coin passage. The washer catcher 32 is pivotally mounted on a pin 34 carried by a bracket 36 fixed to the portion 30 of the movable wall 18 by any convenient means such as a rivet 38 or the like. One end of the washer catcher 32 is formed with a hook 40 which is adapted to extend through an opening 42 formed in the wall 18 so as to be in the path of coins or slugs passing from the opening 16 into the common coin channel. The end of the washer catcher 32 remote from the hook 40 is provided with a weight 44 which biases the catcher 32 so that its hook 40 extends into the coin passage. The arrangement is such that a solid coin inserted in the opening 16 engages hook 40 and pivots the catcher 32 outwardly in the course of the passage of a coin from opening 16 to the common coin slot. The relative angular disposition of hook 40 and the position of weight 44 is such, however, that if a slug formed with a hole is dropped into the opening 16, catcher 32 will initially be pivoted outwardly as the edge of the slug engages hook 40. However, as hook 40 passes over the opening in the slug, weight 44 pivots catcher 32 so that hook 40 engages in the opening in the slug and arrests the movement thereof. Such an arrested coin is discharged from the machine when a scavenging operation is performed in a manner to be described hereinafter.

After having passed by washer catcher 32, coins deposited in the opening 16 travel into the common coin passage formed between movable wall 18 and the plate 10. As can be seen by reference to Figure 6, the initial portion of the bottom of this common coin passage is formed by a flange 46 provided along the bottom edge of the movable wall 18. In order to complete the bottom of the common coin passage, I provide a number of weighing scales separated by bosses mounted on the plate 10. As can best be seen by reference to Figures 2, 6, and 10, these scales include a quarter scale 48 formed with a pair of ears 50 and 52 by means of which the scale is pivotally mounted on a rod 54 carried by a pair of flanges 56 and 58 formed in the plate 10. It will readily be apparent that the scale 48 is mounted on the side of plate 10 other than that on which the movable wall 18 is disposed. Scale 48 extends through an opening 60 formed in the plate 10 so that its end lies adjacent the movable wall 18 to complete the portion of the bottom of the coin path adjacent the entrance to the quarter coin chute. The end of scale 48 remote from the movable wall 18 is provided with a weight arranged to bias the scale to a position to close the portion of the common coin passage adjacent the entrance to the quarter coin chute. This weight may conveniently take the form of a pair of nuts 62 secured to the scale 48 by a screw 64. The arrangement is such that coins which pass by the washer catcher 32 and travel along the portion 46 of the bottom of the common coin passage travel over scale 48. If these coins or slugs have a weight which is at least equal to the weight of a quarter, the scale will be tilted to permit the passage of the coin or slug downwardly out of the common coin passage and into the quarter coin chute, indicated generally by the reference character 65 in Figure 3.

If a coin or slug deposited in the opening 16 weighs less than a twenty-five-cent piece, it continues in its movement along the common coin passage. Following the quarter scale in the common coin passage, I provide a nickel scale 66 which is responsive to a coin or slug weighing at least as much as a five-cent piece. Referring now to Figure 6, in order to complete the portion of the coin passage between the quarter scale 48 and the nickel scale 66, I mount a boss 68 on plate 10 by any convenient means such as a rivet or the like. Referring again to Figures 2 and 10, the nickel scale 66 is formed with a pair of ears 70 and 72 by means of which it is pivotally mounted on rod 54. A weight, which conveniently may be a nut 74 secured to an end of scale 66 by a screw 76, biases scale 66 so that its end remote from nut 74 extends through an opening 78 in plate 10 to complete the portion of the bottom of the coin passage adjacent the entrance to the nickel coin track, to be described hereinafter. All coins which have a weight which is less than a quarter will pass over the scale 48 and travel toward scale 66. If these coins or similarly weighted slugs have a weight which is greater than or equal to that of a five-cent piece, they will tilt scale 66 and pass into the nickel coin track, indicated generally by the reference character 79 in Figure 6. Coins which weigh less than a nickel continue to travel toward the ten-cent coin track, to be described hereinafter. Referring now to Figure 6, in order to complete the portion of the bottom of the common coin passage between the five-cent scale 66 and the entrance to the dime coin track, indicated generally by the reference character 80, I mount a boss 82 on plate 10 by any convenient means such as rivets.

The plate 10 and the eddy current generating magnet carrying plates may advantageously be formed of aluminum, or the like. An insert 11, which can be best seen by reference to Figures 3 and 6, formed of paramagnetic material is placed in an appropriate opening in the

plate 10. The insert 11 is positioned adjacent the magnets which, as will be pointed out hereinafter, are adapted to create eddy currents in the metallic coins falling past them in coin tracks. The paramagnetic material completes the path through which the magnetic flux from the magnets flows.

I have provided a means for arresting the movement along the common coin passage of slugs formed of ferrous material. As can be seen by reference to Figure 1, I 10 mount a ferrous keeper magnet 84 on an arm 86 by any means such as soldering, or the like. Arm 86 is pivotally mounted on a pin 88 carried by the movable wall 18. As a slug of ferrous material passes from the opening 16 downwardly along the common coin passage 15 formed by wall 18 and plate 10, its movement will be arrested by magnet 84. In order to remove such a slug from the common coin passage, I provide means, to be described hereinafter, for pivoting arm 86 in a clockwise direction, as viewed in Figure 1, during a scavenging 20 operation. As arm 86 pivots clockwise, the slug arrested by magnet 84 is drawn upwardly and is engaged with a scraper 90 fixedly secured to movable wall 18 by any convenient means. As magnet 84 and arm 86 continue their upward movement they will move relative to the 25 ferrous slug so that the slug will no longer be held by the magnetic field of magnet 84 but will drop into the slug ejection path in a manner to be described more fully hereinafter.

From the structure thus far described it will readily 30 be appreciated that slugs and coins inserted in the opening 16 are first engaged by the washer catcher 32 which arrests the movement of any spurious or undesired coin or slug formed with a hole. If the coins or slugs pass washer catcher 32, they will travel to the common coin 35 passage formed by movable wall 18, the plate 10, flange 46, the scales 48 and 66, and bosses 68 and 82. As can readily be seen by reference to Figure 6, the common coin passage is inclined downwardly to the right as viewed in the figure so that coins or slugs travel by gravity along 40 this passage. It is to be noted further that the scraper 90 which removes coins caught by ferrous keeper magnet 84 also forms the top of the common coin passage. The distance between this piece and the bottom of the coin passage is such that coins having a diameter greater than that of a quarter will become lodged in the passage. Referring now to Figure 6, a projection 92, which may be a pin or the like, is fixed in the plate 10 over the nickel 45 scale 66. This pin is so spaced from scale 66 that a coin having a diameter which is greater than that of a nickel 50 cannot pass by the pin and over the scale 66. I provide a second projection which may be a pin 94 mounted on plate 10 over the boss 82. Pin 94 is so spaced from the boss 82 that a coin having a diameter greater than a dime but less than a nickel as, for example, a penny, cannot 55 pass by pin 94 and into the dime coin track 80. Thus, a penny may pass pin 92 and has not sufficient weight to tilt scale 66. It is not, however, permitted to arrive at the entrance to the dime coin chute but is arrested by pin 94. Such a coin will be removed from 60 the common coin passage upon a scavenging operation in a manner to be described hereinafter. It can be seen that coins and slugs which pass by washer catcher 32 travel down the common coin passage where they are classified and separated according to weight by the scales 48 and 65 66 and according to diameter by scraper 90, pin 92, and pin 94. The spacing between the movable wall 18 and the plate 10 is so selected that a coin or slug which is thicker than a true five-cent piece will become lodged in the common coin passage. In this manner, not only diameter and weight, but also thickness of a coin is measured. It will be appreciated that slugs of ferrous material will be arrested by the ferrous keeper magnet 84.

Coins or slugs of the proper diameter and thickness which have a weight sufficient to tilt the twenty-five-cent scale 48 pass out of the common coin passage and down-

wardly into the twenty-five-cent coin track, indicated generally by reference character 65. Referring now to Figure 3, a portion 96 of the plate 10 is bent inwardly to receive coins from the scale 48 and direct them toward the side of plate 10 other than that on which movable wall 18 is mounted. After being directed from one side to the other of plate 10 by portion 96, coins or slugs received from scale 48 travel by gravity along the twenty-five-cent coin track 65. Coin track 65 is formed by a curved track 98 fixed to the plate 10 by any suitable means. Coins or slugs are directed along this track by a triangular member 100 welded to plate 10. The coin track 65 has one side thereof formed by the plate 10 and the paramagnetic insert 11. The other side of this quarter coin track is formed by a removable quarter eddy current magnet mounting plate 102 shown in Figure 4. As can be seen by reference to Figures 2 and 3, mounting plate 102 is formed with a pair of bifurcated flanges 104 and 106 on the bottom thereof. Plate 10 carries a rod 108 mounted in a pair of brackets 110 and 112 welded to bosses 114 and 116 fixed to the plate 10. The bifurcated flanges 105 and 106 may be engaged with rod 108 and the removable eddy current magnet mounting plate swung into place in the assembly. A pin 118 carried on piece 100 engages an opening 120 in plate 102 properly to register plate 102 with the plate 10. After coins or slugs travel by gravity down the track 98, they are directed substantially horizontally off the track 98 and into the field of an eddy current magnet 122 fixed on plate 102 by any convenient means such as screws 124. It is well known that a metallic member passing through a magnetic field will have eddy currents generated therein which exert a braking effect thereon, thus affecting the rate of travel of the element through the field. When such an element is projected substantially horizontally into such a magnetic field, it tends to drop under the influence of gravity, but its trajectory is affected by the eddy current braking resulting from the magnetic field. I have arranged my eddy current magnet 122 to affect the trajectories of coins or slugs leaving the track 98 so that genuine quarters will be directed to an acceptance opening and spurious coins or slugs will be directed toward a rejection opening. It will readily be appreciated that as coins or slugs which have traveled down the track 98 under the influence of gravity enter the field of eddy current magnet 122, they have a certain initial velocity. If this initial velocity is high, the proportionate effect of the eddy current braking resulting from magnet 122 will not be sufficiently great to cause any appreciable difference in trajectories of coins of various compositions. In order to reduce this initial velocity so that the proportionate effect of the eddy current braking on the over-all trajectory of the coin will be greater, I provide a braking means for reducing the initial velocity of coins or slugs as they leave track 98 and enter the field of magnet 122. This braking means includes an arcuate arm 126 pivoted on a pin 128 carried by plate 10 and normally resting under the influence of gravity on a projection 130 on the plate 10. As a coin or slug approaches the end of track 98, its edge is engaged by the end of arm 126 to pivot the arm in a counterclockwise direction as viewed in Figure 3. It will readily be appreciated that this action substantially reduces the random component of initial velocity of a coin or slug as it enters the path of eddy current magnet 122. It will readily be appreciated also that while all coins entering track 65 from scale 48 have a weight which is at least equal to the weight of a quarter, they may be of varying weights. Owing to friction differences of coins of different weights on the coin track, different coins may arrive at the end of track 98 with different velocities. The brake effect of arm 126 reduces this random difference in velocity of coins or slugs of differing weights as they enter the field of eddy current magnet 122 so that all coins or slugs enter the field with substantially the same velocity. Consequently, the sen-

sitivity of the eddy current braking separation of coins from slugs is not appreciably affected by variance in the respective weights of coins coming from scale 48.

As has been mentioned hereinabove, eddy current magnet 122 affects the trajectories of coins or slugs passing through its field, depending upon the composition of the coin or slug. The effect of the eddy current magnet on the coin or slug may readily be related to the physical properties of the material from which the coin or slug is formed. For example, if a coin has a high conductivity, the braking effect of the eddy current magnet will be large. If, on the other hand, the coin or slug has a low electrical conductivity, the braking effect of the eddy current magnet will be less. If a coin or slug has a large mass, the braking of the eddy current device will not have as great an effect on its trajectory, since the momentum of the coin or slug passing through the eddy current magnet field will be high. The relationship between the trajectories of coins or slugs of various materials passing through the field of the eddy current magnet 122 may be expressed in terms of residual momentum, which, assuming the velocities of all coins or slugs to be equal, is proportional to the product of the electrical resistivity and the specific gravity of the material from which the coin or slug is formed. The following table represents a calculation of the relative residual momentum which may be expected of various materials. The values given are by way of example only, and the quantity designated residual momentum is calculated only for the purpose of illustrating the relative trajectories which may be expected for various materials of which coins and slugs may be formed.

TABLE
Residual momentum=f(ρδ)

Material	Resistivity (ρ), Microhm Centimeters at 20° C.	Specific Gravity (δ)	Residual Momentum
Aluminum.....	2.80	2.70	7.56
Copper.....	1.72	8.90	14.31
Silver.....	1.59	10.60	16.70
Zinc.....	5.80	7.10	41.18
Brass.....	7.00	8.60	60.20
Nickel.....	7.80	8.75	69.35
Lead.....	22.00	11.40	260.80
German Silver.....	33.00	8.40	277.20

From the foregoing table it can be seen that the eddy current magnet will have relatively little effect on materials such as German silver and lead. On the other hand, the table indicates that the eddy current magnet has a relatively much greater effect of materials such as copper and aluminum. Lying between these two groups is silver, the material of which twenty-five-cent pieces are formed. A schematic view of the relative trajectories of these various materials is shown in Figure 17 with residual momentum plotted on a logarithmic scale.

The plate 10 is formed with an opening 132 adjacent the bottom thereof into which true quarters are to be directed. The portion of plate 10 forming the base of the opening 132 is provided with a projection 134 extended outwardly as viewed in Figure 3 to direct coins into the opening 132. The boss 116 on the bottom of plate 10 is adapted to direct spurious coins toward an opening 136 formed at the right-hand side of the bottom of the assembly by plates 102 and 10. In order to direct true quarters or slugs toward the proper respective openings 132 or 136 in accordance with the extent to which their trajectories are affected by the eddy current braking means, I provide the plate 102 with a coin bouncing means and with a separating point both disposed in the path of various slugs or coins which have passed through the field of magnet 122. As can be seen by reference to Figures 2 and 3, the bouncer 138 may conveniently be formed of a bent wire adjustably carried on plate 102 by a screw 140

and having an end extending through a slot 142 formed in plate 102. A pivoted separator 144 is carried on a pin 146 fixed on a bracket 148 having a bifurcated end by means of which it is adjustably mounted on plate 102 by a screw 150. Separator 144 has an end extending through an opening 152 in plate 102. The arrangement is such that the edge of separator 144 is presented to coins passing downwardly from track 98 toward the separator.

The disposition of the bouncer 138 and the separator 144 in the assembled position is indicated in phantom in Figure 3. The position of bouncer 138 is such that it lies in the path of a spurious quarter which is formed of a material which is affected to a lesser degree by the eddy current braking magnet 122 than a genuine coin. The path of such a spurious coin is indicated in dotted lines in Figure 3. As can be seen by reference to the figure, such a coin, which may be formed of a material such as German silver, lead, nickel, brass, zinc, or the like, travels through the field of magnet 122 and strikes bouncer 138 so as to be directed downwardly toward the separator 144. Its path is such that it strikes the right-hand side of separator 144 as viewed in Figure 3. It is thereafter directed toward the opening 136 from whence it passes to a suitable slug or coin return receptacle (not shown). A coin formed of a material such as aluminum or copper which is affected greatly by the eddy current braking magnet 122 follows a path indicated in broken lines in Figure 3. After leaving track 98 such a coin drops rapidly to engage the right-hand side of separator 144 as viewed in Figure 3. Separator 144 directs this coin toward the slug opening 136. A good coin formed of silver follows a path indicated by the dot-dash lines of Figure 3. The trajectory of a good coin is such that after leaving the field of magnet 122 it strikes the left-hand side of separator 144 as viewed in Figure 3 and is directed toward projection 134 which deflects the coin into the opening 132 from whence it passes into the quarter discharge opening of the assembly.

As can be seen by reference to Figures 3 and 5, a quarter deposited in the opening 16 is first sensed by the washer catcher 32 from which it passes into the common coin passage where it is sized for diameter by scraper 90 and weighed by scale 48. After tilting scale 48 it passes downwardly along coin track 98 to be engaged by brake 126 which determines its initial velocity as it passes into the field of eddy current magnet 122. The magnetic field of eddy current magnet 122 so affects the trajectory of a true quarter that it is directed into the opening 132 by separator 144 and projection 134 from whence it passes outwardly from the bottom of the assembly through a true quarter discharge opening 135.

Referring now to Figures 6 and 7, the nickel and dime coil tracks 79 and 80 are arranged on the other side of plate 10 from the quarter coin track. The nickel coin track which receives coins and slugs of proper diameter and weight from scale 66 is formed by a depending curved portion 146 of boss 82. One side of the nickel coin track 79 is formed by plate 10 and paramagnetic insert 11. The other side of the coin track is formed by a removable nickel and dime eddy current generating magnet mounting plate 148 illustrated in Figure 7. As can be seen by reference to Figures 1 and 7, plate 148 is formed with a pair of bifurcated flanges 150 and 152 adjacent the bottom thereof. A rod 154 is mounted at one end in a bracket 156 welded to a boss 158 fixed on plate 10. The other end of rod 154 is fixed in side 14 of the assembly. It will readily be appreciated that plate 148 may be assembled on plate 10 by engaging the bifurcations of flanges 150 and 152 with the rod 154 and swinging plate 148 upwardly to the position shown in Figure 1. It will be appreciated that, owing to the insert 11 of paramagnetic material in plate 10, not only do I provide for the completion of the flux path of the fields of the eddy current magnets of my device, but I am

enabled to retain the eddy current generating magnet mounting plates in their assembled positions. Plate 148 carries a five-cent eddy current braking magnet 160 mounted thereon by screws 162. The disposition of magnet 160 when plate 148 is in the assembled position is indicated in phantom in Figure 6. It is arranged adjacent the end of track 79 so that nickels and slugs leaving portion 146 must pass through the field of the magnet. As was explained in connection with the twenty-five-cent coin track, eddy current magnet 160 affects the trajectories of five-cent coins and slugs leaving track 146. In order to ensure that five-cent coins and slugs leaving track 79 have approximately the same initial velocity when they enter the field of the magnet 160 and to minimize the effect of random variations in the respective weights of five-cent coins and slugs, I pivotally mount a five-cent coin brake 164 on a pin 166 in plate 10. Brake 164 is biased by weights, which may be nuts 168 carried by a screw 170 fixed in an end of brake 164, to a position where five-cent coins and slugs passing downwardly along extension 146 will be engaged by the brake. If necessary, slots 172 may be provided in plate 10 and plate 148 to permit movement of the screws 170 and the nuts 168 carried thereby. The path of a spurious nickel formed of a material which is not appreciably affected by the eddy current braking magnet 160 is indicated in Figure 6 by a dotted line. As can be seen by reference to Figure 17, the materials which are affected by the eddy current braking magnet to a lesser degree than is nickel are German silver and lead. After having left the field of eddy current magnet 160, such coins strike the inclined edge 174 of an anvil 176 secured to plate 10 by screws 178. Since such materials have a low coefficient of restitution, they bounce from surface 174 with reduced velocity and drop toward a slug opening 179 formed by plate 10, plate 148, and boss 158. The path of spurious nickels, which are formed of material which is affected by the eddy current braking magnet to a greater degree than is nickel, is indicated in Figure 6 by broken lines. Such spurious coins are affected by eddy current magnet 160 to a degree where they pass between anvil 176 and a separating point 180 carried by plate 10 without striking either the anvil or the separating point. They pass directly into the slug opening. The path of genuine nickels is indicated by dot-dash lines in Figure 6. Such coins are affected by the eddy current magnet to a degree where they strike the surface 174 of anvil 176. Since they are formed of an alloy which has a relatively high coefficient of restitution, they bounce off surface 174 and over separating point 180. After passing over separating point 180 these coins are engaged by a lateral projection 182 formed in plate 10. Projection 182 directs genuine five-cent pieces through an opening 184 formed in plate 148. As can be seen by reference to Figures 1 and 8, opening 184 is provided with a cover 186 which directs nickels to a five-cent-piece discharge opening in the bottom of the assembly. This opening is indicated by the reference character 188 in Figure 8.

Coins or slugs which are small enough in diameter and thin enough to pass through the common coin passage without engaging pin 92 and which do not have a weight sufficient to tilt scales 48 or 66 pass under pin 92 toward pin 94. If the coins or slugs have a diameter which is greater than that of a dime, they will be caught by the pin 94 and will thus be prevented from entering the ten-cent coin track 80. If, however, the coins have a diameter which is equal to or less than a dime, they will pass into the coin track 80, the bottom of which is formed by a curved surface 190 provided by a boss 192 secured to the plate 10. In order to test such coins or slugs according to the material of which they are constituted, I mount a ten-cent eddy current braking magnet 194 on the plate 148 by any means such as screws 196. Magnet 194 is indicated in phantom in Figure 6 and is so posi-

tioned that coins or slugs leaving the track surface 190 come under the influence of the magnetic field provided by the magnet 194. The trajectories of such coins or slugs will be affected in accordance with the residual momentum of the materials of which they are constituted. The action of this eddy current generating magnet is the same as that of the five-cent and twenty-five-cent eddy current braking magnets. In order to ensure that all coins or slugs enter the field of eddy current magnet 194 at substantially the same initial velocity, I pivotally mount the brake 198 on a pin 200 carried by plate 10. A suitable weight which may be nuts 202 carried by a screw 204 in the end of brake 198 remote from pin 200 biases the brake to a position where it is engaged by the edge of a coin or slug passing down the dime coin track 80. Suitable openings 206 may be provided in the plates 10 and 148 to permit movement of the nuts 202 carried by screws 204. In order to separate coins from slugs their paths of travel are caused to be varied by the eddy current magnet 194 for cooperation with a bouncer 208 positioned in the path of certain of the spurious coins leaving the field of magnet 194 with a residual momentum higher than that of a good coin. Bouncer 208 is similar to the quarter bouncer 138 provided in the quarter coin track. It is formed of a length of wire and is adjustably carried by a screw 210 secured to the plate 148. As can be seen by reference to Figures 1 and 7, bouncer 208 extends into the space between plates 10 and 148 through a slot 212. An additional separator 214 is pivotally carried by a pin 216 fixed in a bracket 218 adjustably mounted on plate 148 by a screw 220. Separator 214 extends through an opening 222 into the space between plates 10 and 148 to separate coins in a manner to be described.

The path of spurious coins formed of material which is affected by the eddy current braking magnet 194 to a lesser degree than is silver, of which dimes are formed, as indicated in Figure 6 by the dotted line. As can be seen by reference to the figure, such a spurious coin is not slowed down to an appreciable degree by eddy current magnet 194, but follows a path such that it strikes the left edge of separator 214. A projection 224 formed on boss 158 provides a track along which such a coin is guided to the slug opening 179. A spurious coin which follows the dotted path shown in Figure 6 would be formed of a material such as German silver, lead, nickel, brass, or zinc, as is indicated in Figure 17. The path of a spurious coin which is formed of a material which is affected to a greater degree than is coin silver is indicated by the broken line in Figure 6. Such a spurious coin or slug would be one formed of copper or aluminum, as indicated by Figure 17. Since such a spurious coin is greatly retarded by the effect of the eddy current braking magnet 194, it drops substantially vertically from the surface 190 to a point where its edge engages the bouncer 208. Such a coin bounces off bouncer 208 to the guide 224 from whence it is directed toward the slug opening 179. It is to be noted that spurious coins which are retarded to a greater degree than are silver coins are formed of materials which have a sufficiently high coefficient of restitution to cause them to bounce from bouncer 208 to the guide 224. The path of a genuine dime is indicated in Figure 6 by the dot-dash lines. As can be seen by reference to the figure, the path of such a coin is so affected by the eddy current braking magnet 194 that it passes between separator 214 and bouncer 208 after having left the field of magnet 194. After having passed between separator 214 and bouncer 208, a genuine dime is engaged by a lateral deflector 226 extended outwardly from plate 10 at the base of opening 132, as viewed in Figure 6. Projection 226 deflects the genuine dime laterally of the plate 10 and into a dime discharge opening 228 formed in the bottom of the assembly by the portion of plate 10 below opening 132, by bosses

114 and 116, and by the quarter eddy current magnet mounting plate 102. This opening 228 can best be seen by reference to Figures 3 and 9.

From the structure thus far described it will be seen that I have provided an assembly which separates genuine coins from spurious coins and which classifies respective genuine coins as nickels, dimes, or quarters. Slugs formed with holes are caught by washer catcher 32. Ferrous slugs are arrested in their movement along the common coin passage by ferrous keeper magnet 84. Slugs or coins which are too thick or which have too large a diameter are arrested in their movement along the common coin passage. It is to be noted, moreover, that my mechanism arrests the passage of undesired coins such as pennies, or the like, along the common coin passage. It will be appreciated that when certain types of slugs or undesired coins have been deposited in opening 16 they may become caught or jammed in the common coin passage. If some means were not provided for removing such slugs and undesired coins from the assembly, further operation of the device would be impossible, since genuine coins could not by-pass the caught coins and slugs. I have provided a scavenging mechanism for removing such caught coins and slugs from the common coin passage and feeding them to a slug discharge opening.

Referring now to Figures 1 and 2, this scavenging mechanism includes a scavenging lever 230 pivotally mounted on a screw 232 carried by the upper portion of plate 10 adjacent side 12. Lever 230 is normally urged in a clockwise direction as viewed in Figure 2 by a spring 234, one end of which engages a pin 236 in plate 10 and the other end of which engages an offset portion 238 of lever 230. A washer 240 retains the coiled portion of spring 234 on screw 232.

As can be seen by reference to Figures 2, 6, and 10, in order to provide a means for moving coins caught on scales 48 and 66 laterally off the scales, I swingably mount a plate 242 on a rod 244 fixed between the flanges 56 and 58 of plate 10. Plate 242 is provided at its base with a pair of laterally extending fingers 246 and 248 which extend through a slot 250 formed in plate 10 above the openings 60 and 78 through which scales 48 and 66 extend. Plate 242 is normally urged by a spring 252 in a direction so that the fingers 246 and 248 extend through opening 250 into the common coin passage. Spring 252 surrounds rod 244 and has one of its ends positioned against plate 10 and the other end positioned against the plate 242. Plate 242 is formed with a lug 254 along its upper edge. Lug 254 carries a pin 256 which is engaged by a projection 258 upstanding from the upper edge of lever 230. As lever 230 is urged in a clockwise direction, as viewed in Figure 2, by the action of spring 234, projection 258 engages pin 256 to move fingers 246 and 248 out of the coin passage against the action of spring 252. The movement of both plate 242 and lever 230 is limited by the engagement of lug 254 with the surface of plate 10. Normally, therefore, when the scavenging lever is not actuated, fingers 246 and 248 are positioned out of the common coin passage.

Referring again to Figure 2, lever 230 is resiliently connected with movable wall 18 by a coil spring 260 fixed at one end in an opening 262 in lever 230 and connected at the other end to a pin 264 carried by the ear 20 of movable wall 18. Spring 260 is not normally under tension so that movable wall 18, owing to the influence of gravity, occupies a position where it completes the common coin passage. When, however, lever 230 is moved against the action of spring 234, spring 260 is tensioned to pivot movable wall 18 in a direction to move wall 18 away from plate 10 and thereby open one side of the coin passage. At the same time, as lever 230 is moved against the action of spring 234, projection 258 is disengaged from pin 256 and plate 242 may pivot under the action of spring 252 so that fingers 246 and 248 enter the com-

mon coin passage through the opening 250. The arrangement of the parts is such that when lever 230 is actuated, pin 256 is first released to permit fingers 246 and 248 to engage coins or slugs on scales 48 and 66 to move them sidewise into engagement with movable wall 18. Upon continued movement of lever 230 wall 18 moves and the coins or slugs are swept off the scales by fingers 246 and 248. After fingers 246 and 248 have moved a sufficient distance to sweep caught coins or slugs off the scales, the movement of plate 242 is arrested by the engagement of the plate 242 with the portion of the plate 10 above the slot 250. Continued movement of lever 230, however, pivots movable wall 18 further away from plate 10. Coins caught between the movable wall and the fingers 246 and 248 are thereby released and permitted to drop into a slug rejection chute, indicated generally by reference character 264 in Figure 1. As can be seen by reference to Figures 1 and 15, chute 264 is formed by a side member 266, an inclined bottom portion 268 under the scales, and an end wall 270. The other end of the chute is closed by side 12. This scavenger chute directs undesired coins or slugs to a suitable slug receptacle.

Since ferrous keeper magnet lever 86 is pivoted on movable wall 18, as the wall 18 is pivoted outwardly from the plate 10 magnet 84 will also be moved outwardly and will carry a spurious coin caught thereby out over the scavenging chute 264. In order to actuate magnet 84 so that a slug of magnetic material caught thereby is scraped from the face of the magnet by scraper 90 at the time when the magnet and slug are disposed over the scavenging chute, I fix a rod 272 on the end of lever 230 remote from its pivotal mounting 232. As lever 230 is moved during a scavenging operation, rod 272 engages the end 274 of lever 86 which is on the side of pivot 88 remote from the magnet 84. As a result of this engagement, lever 86 is moved in a clockwise direction about pivot 88, as viewed in Figure 1, and a ferrous slug held by magnet 84 engages with scraper 90 and is held thereby while magnet 84 moves beyond the scraper to release the ferrous slug and thus permit it to drop into the scavenging chute 264. It is to be noted that movable wall 18 is formed with an opening 275 which permits the movement of rod 272 relative to the movable wall. Plate 10 is also formed with an opening 277 which permits this movement.

As has been described hereinabove, the washer catcher 32 is pivoted on the portion 30 formed on movable wall 18. As the movable wall pivots outwardly from plate 10, the washer catcher 32 likewise pivots outwardly and releases a slug or coin formed with a hole therein. It will be appreciated that the washer catcher 32 is disposed over the vertical portion of the scavenging chute 264 so that a coin released by the washer catcher drops directly into the scavenging chute.

A possibility exists that coins such as pennies or slugs which have a diameter which is larger than a dime but less than a nickel may become caught in the common coin passage between pin 94 and boss 82. In order to dislodge such coins or slugs I have provided a sweep arm for sweeping across this portion of the common coin passage each time the scavenging lever 230 is operated. As can be seen by reference to Figure 16, this wiper 276 is pivoted on a pin 278 carried by plate 10. A spring 280 surrounds pin 278 and is retained thereon by a washer 282. One end of spring 280 is positioned against a pin 284 carried by plate 10 and the other end of spring 280 bears against a pin 286 carried by wiper 276. In this manner the spring biases the wiper to rotate in a counterclockwise direction as viewed in Figure 16. This movement of the wiper is limited by its engagement with rod 272. As rod 272 is moved downwardly in response to the actuation of the scavenger lever 230, wiper 276 sweeps across the common coin passage adjacent the entrance to the dime coin track to dislodge any coin caught in the passage adjacent this point. Caught coins engaged by

a wiper 276 are knocked back along the common coin passage toward the nickel scale 66. It will be remembered that at this time the nickel scale is not tilted so that a possibility exists that a coin knocked back by wiper 276 may become lodged on the nickel scale. In order to clear the nickel scale if this occurs, I provide a means for dumping the nickel scale when the scavenging mechanism operates.

Referring now to Figure 2, the quarter coin track brake 126 is provided with a fitting 288 having an opening in which I mount a wire whisker 290 by means of a screw 292. Brake 126 is also formed with an offset projection 294 which is arranged to be engaged by the end of lever 230 carrying pin 272 as the lever moves downwardly. When projection 294 is so engaged, brake 126 is pivoted in a counterclockwise direction as viewed in Figure 2 and whisker 290 engages the portion of scale 66 carrying screw 76 to tilt the scale in a direction to dump a coin or slug forced back thereon by wiper 276 into the scavenger chute 264.

I have provided my improved coin separator and slug ejector with an antitilt means for preventing a dishonest person from inducing a slug to pass through the separator and into the coin actuated mechanism by tilting the machine. Informed tilting of the machine may alter the coin paths to cause a slug to pass into chutes for genuine coins, instead of into the slug chute. As can be seen by reference to Figure 1, an antitilt lever 296 is pivotally mounted on a pin 297 in the plate 10. One end of lever 296 is formed with a re-entrant portion 298. The other end of lever 296 carries a weight 300 which biases the lever to a position where the re-entrant portion 298 normally lies adjacent the washer catcher 32. When lever 296 is in its normal position, the re-entrant portion 298 permits the washer catcher 32 to be pivoted by a coin passing through the opening 16. When the machine and the separator assembly carried thereby are tilted in either direction from the position shown in Figure 1, lever 296 pivots with respect to the plate 10 so that one of the sides of the re-entrant portion 298 engages and immobilizes washer catcher 32. It will be appreciated that in this condition of the parts, no slug or coin may pass by the immobilized washer catcher 32. Such a coin or slug, except one formed with a hole, will pass by the washer catcher when the machine is returned to level position. A slug or spurious coin will then be ejected in the normal manner. It will be appreciated that the pivotally mounted brakes in the respective coin tracks may also function as antitilt devices to prevent further passage of coins or slugs along the coin tracks when the machine is tilted, or to interfere with the paths of travel of coins to effect their rejection when the assembly is tilted.

In operation, the user deposits coins of the proper denominations into the coin slot 16. If genuine coins are deposited, they will pass the washer catcher 32 and will pivot it about the pin 34 during their passage. The coins then travel down the common coin passage of the assembly. Quarters tilt the quarter coin scale 48 and pass into the quarter coin track 65 and downwardly along track 98 until they strike damper brake 126. After striking damper brake 126 they pass through the field of magnet 122 and are sufficiently retarded thereby so that they strike the left-hand side of separator 144, as viewed in Figure 3, and projection 134 deflects them into the genuine quarter discharge passage.

If a ferrous slug has been deposited, it will be caught by ferrous keeper magnet 84. If a nonferrous, spurious quarter of proper thickness, diameter, and weight is deposited, it will pass into the quarter coin track 65. Depending upon the material of which it is constituted, the slug will either bounce off bouncer 138 after passing through the field of magnet 132, or will drop directly to the right-hand side of separator 144. From separator 144 such a spurious coin will be deflected into the 75 bad quarter discharge opening 136.

Ferrous nickel or dime slugs will be caught by the ferrous keeper magnet in the same manner as are ferrous quarter slugs. Similarly, spurious nickels or dimes formed with holes will be caught by washer catcher 32. Nickels of the proper thickness, diameter, and weight ride down the common coin passage until they engage pin 92 where they tilt the scale 66 and drop into the nickel coin track 79 so as to travel along track 146. The movement of true nickels will be so affected by the nickel eddy current magnet 160 that such nickels bounce off anvil 174 so that projection 182 will deflect them to pass out of the acceptable nickel opening 183. This path of movement can be seen by reference to Figure 8. Spurious nickels, which are not retarded by the eddy current magnet 160 so that they strike anvil 174, and which are formed of a metal having a relatively low coefficient of restitution, will merely drop off the anvil and pass out of opening 179. Spurious nickels which are retarded to a greater degree than are true nickels fail to reach anvil 174 and pass directly downwardly through opening 179. As can be seen by reference to Figure 9, true dimes deposited in the opening 16 pass downwardly over both the quarter and nickel scales and into the dime coin track 80. The movement of true dimes is affected by eddy current magnet 194 to such an extent that true dimes are engaged by projection 226 and directed into the good dime acceptance opening 228. The path of spurious dimes, which are not affected to any appreciable degree by the eddy current magnet 194, is such that they drop to the left-hand side of separator 214 and are directed by guide portion 224 into the slug discharge opening 179. Spurious dimes whose movement is retarded considerably by eddy current magnet 194 strike bouncer 208 from whence they bound onto guide 224 which directs them to opening 179.

After a slug or undesired coin has been caught for any reason in the common coin passage, it must be ejected therefrom before the next succeeding operation of the machine being protected can take place. Such a spurious coin may be caught by washer catcher 32, by the ferrous keeper magnet 84, or may become lodged in the passage because of its improper thickness or diameter. In order to dislodge and discharge a caught coin or slug, the scavenger lever 230 is pivoted about pivot 232 in a counterclockwise direction. This movement causes fingers 246 and 248, which are formed on the plate 242, to move into the opening 250 and to pass across the coil passage so as to clamp caught coins and slugs against the movable wall 18. At the same time wall 18 is moved outwardly. After a predetermined amplitude of motion, the movement of plate 242 is arrested so that clamped coins are released upon further movement of movable wall 18, permitting the caught slugs to be dropped into the slug channel 264. As the movable wall 18 moves outwardly, spurious coins formed with holes which have been caught by washer catcher 32 are likewise released and drop into the slug ejection opening. Then too, as movable wall 18 moves outwardly, rod 272 on lever 230 engages the end 274 of arm 286 which carries the ferrous keeper magnet 84 to move the magnet 84 upwardly as viewed in Figure 1. As the magnet moves upwardly, a coin caught thereby engages scraper 80 and is removed from the face of the magnet to be dropped into the slug path 264. As can be seen by reference to Figure 16, rod 272 in its downward movement also engages wiper 276 to pivot it in a clockwise direction against the action of spring 280. Wiper 276 sweeps across the portion of the common coin passage adjacent the entrance to the dime coin track and forces a coin, caught by pin 94, back along the common coin passage. In order to ensure that such a coin is not retained on the nickel coin scale, whisker 290 engages and tilts this scale to release a coin which may be positioned thereon as the wiper is operated. The antitilt lever 296 operates in the manner described hereinabove to prevent coins and slugs from

passing through the assembly to an acceptance opening when the machine is tilted.

It will be seen that I have accomplished the objects of my invention. I have provided an improved coin separator and slug ejector which is simple in construction, certain in operation, and which may readily be disassembled to permit cleaning thereof. My improved coin separator and slug ejector prevents the passage of slugs formed with holes and ferrous slugs through the assembly. It separates deposited coins into their respective denominations and tests the separated coins to determine the material of which they are constituted. Spurious coins which are not formed of the proper material are directed to a slug receptacle, while genuine coins are directed to their proper respective acceptance openings. My assembly is provided with means for rejecting slugs or undesired coins which have been caught by the apparatus. My assembly may be accurately and expeditiously adjusted. It may be quickly and readily dismounted for easy cleaning. My device cannot be defeated by tilting the assembly and altering the paths of travel of the coins. My separator not only measures the diameter and thickness of the coins, but also weighs them. The electric conductivity, the specific gravity and the elasticity of the material of the coins are utilized in my assembly. The brakes of my assembly reduce random variations in the coins being tested.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is therefore to be understood that my invention is not to be limited to the specific details shown and described.

Having thus described my invention, what I claim is:

1. In a device of the character described, means forming a common coin passage, means forming a coin slot for directing coins inserted therein to said common coin passage, a washer catcher, means pivotally mounting said washer catcher between said coin slot and the common coin passage, means normally biasing said washer catcher to a position where it extends into the space between the coin slot and the common coin passage, the arrangement being such that a coin pivots said washer catcher and passes by the washer catcher into the common coin passage while a slug formed with a hole is caught and retained thereby, an antitilt lever, means pivotally mounting said antitilt lever adjacent the washer catcher, means formed on said antitilt lever for preventing pivotal movement of said washer catcher when the machine is tilted, and means biasing said antitilt lever to a position where the washer catcher is permitted to pivot.
2. In a device of the character described a common coin passage including a first wall formed by a fixed plate and a second wall, means mounting said second wall for pivotal movement away from said fixed plate, means normally biasing said movable wall toward said fixed plate, means forming a coin slot for directing coins and slugs inserted therein into the common coin passage, a ferrous keeper magnet for arresting the movement of slugs formed of ferrous material, means pivotally mounting the ferrous keeper magnet on the movable wall adjacent the entrance to the common coin passage about an axis substantially perpendicular to the plane of said movable wall, scavenging means for moving said movable wall away from the fixed plate against the action of said biasing means, said scavenging means actuating said magnet mounting means to move said magnet away from the coin passage as said movable wall moves away from the fixed plate, and means for retaining slugs caught by said magnet as said magnet is moved away from the coin passage.
3. In a device of the character described means form-

ing a common coin passage, said means including a support and a scale, means pivotally mounting said scale on the support, biasing means normally urging said scale to a position to form a portion of the bottom of said common coin passage, the arrangement being such that a coin or slug having a predetermined weight actuates said scale against the action of the biasing means, diameter sizing means disposed in said coin passage in a position to be engaged by coins and slugs passing over said scale, said diameter sizing means being adapted to arrest coins having a diameter greater than a predetermined diameter, a sweep arm pivotally mounted adjacent said diameter sizing means, means normally biasing said sweep arm to a position out of the common coin passage, scavenging means operable to urge said sweep arm into said passage against the action of said biasing means to dislodge a coin or slug caught by said diameter sizing means and urge it toward said scale, and means operable by said scavenging means to pivot said scale to permit a dislodged coin or slug to be dropped out of the coin passage.

4. A coin separator and slug ejector for coin operated machines including in combination a common coin passage, a coin slot for directing coins deposited therein to said common coin passage, a plurality of coin tracks disposed below said common coin passage, said common coin passage including means for separating coins according to denomination by weight and means for directing separated coins and slugs to respective coin tracks, means forming an acceptance opening and a rejection opening adjacent the respective coin tracks, a washer catcher disposed between said coin slot and said coin passage for arresting the movement of slugs formed with holes from the coin slot to the coin passage, said washer catcher adapted to move in response to the passage of a coin from said coin slot to said coin passage, an antitilt lever mounted adjacent said washer catcher and arranged to lock said washer catcher against movement when the machine is tilted and means for affecting the trajectories of coins and slugs leaving a coin track in a manner to direct true coins to said acceptance opening and spurious coins to said rejection opening.

5. A coin separator and slug ejector for coin operated machines including a common coin passage having a first wall formed by a fixed plate and having a second wall formed by a movable plate pivotally mounted on the fixed plate, a coin slot for directing coins deposited therein to said common coin passage, a plurality of coin tracks disposed below said common coin passage, said common coin passage including means for separating coins according to denomination by weight and including means for directing separated coins and slugs to respective coin tracks, means forming an acceptance opening and a rejection opening adjacent the respective coin tracks, means for affecting the trajectories of coins and slugs leaving a coin track in a manner to direct true coins to said acceptance opening and spurious coins to said rejection opening, a finger, means mounting said finger on said fixed plate for pivotal movement into and out of the coin passage, means normally biasing said finger to a position

- out of the common coin passage, scavenging means adapted when operated to move said finger against the action of said biasing means into the common coin passage to clamp a coin or slug disposed in said passage between said finger and said movable wall, said scavenging means including means for concomitantly moving said finger and said movable wall to carry a clamped coin or slug out of the common coin passage, means permitting relative movement between said finger and said movable wall and means for arresting the movement of said finger after said concomitant movement of said finger and said movable wall to release said coin upon further movement of said movable wall.
6. In a device of the character described, means forming a common coin passage, means forming a coin slot for directing coins inserted therein into said common coin passage, a ferrous keeper magnet for arresting slugs formed of ferrous material, means pivotally mounting said ferrous keeper magnet for movement about an axis which is normally substantially perpendicular to the plane of said coin passage adjacent the entrance to the common coin passage, means mounting said magnet mounting means for movement about an axis substantially parallel to the plane of said coin passage, scavenging means for pivoting said magnet mounting means away from the common coin passage while moving said magnet around its pivotal mounting means, a spurious coin chute adjacent said common coin passage and means responsive to movement of said magnet about its pivotal mounting means for causing a slug arrested by said magnet to fall into said spurious coin chute when said magnet mounting means pivots away from the common coin passage.
